UNITED STATES PATENT OFFICE.

LEWIS D. RANK, OF WILLIAMSPORT, PENNSYLVANIA.

BUCKLE.

SPECIFICATION forming part of Letters Patent No. 586,746, dated July 20, 1897.

Application filed March 8, 1897. Serial No. 626,532. (No model.)

To all whom it may concern:

Be it known that I, LEWIS D. RANK, a citizen of the United States, residing at Williamsport, in the county of Lycoming and State of Pennsylvania, have invented certain new and useful Improvements in Buckles; and I do hereby declare the following to be a full, clear, and exact description of the invention, such as will enable others skilled in the art to 10 which it appertains to make and use the same.

My invention relates to improvements in buckles, and more particularly to harness-buckles; and the object thereof is to so construct the same that it will be simple, cheap, durable, strong, and easily manipulated.

With these and other objects in view my invention consists in the construction, arrangement, and combination of parts, as will be first fully pointed out in the specification and 20 then claimed.

In the drawings forming a part of this specification, and in which like symbols of reference represent corresponding parts in the several views, Figure 1 is a plan view of my 25 invention, showing the same in operative position applied to a trace. Fig. 2 is a side view of the same. Fig. 3 is a side view of the main member of the buckle, and Fig. 4 is a similar view of the other member of the buckle.

30 A and B represent the two members forming the buckle. The member A is a metallic frame substantially rectangular in form and having the two upper portions a' a^2 lying substantially in the same plane. The lower portion a^3 lies in a different plane, the space between the two planes being equivalent to the thickness of the strap to which it is to be applied. This lower portion a^3 has also formed depressions or bearings a for a purpose which 35 will be presently explained. The bar A' joins the two sides of the lower portion of the frame A and is adapted to hold the strap which is inserted within the same.

The member B is composed of a square portion b' , which terminates in the center in 40 journals or trunnions b^2 and has a triangular tongue-plate B' , at the end of which is formed the tongue or stud of the buckle b . On a bracket, also formed integral with the member B, is a frame b^3 , which constitutes an axle 45 for a friction-roller b^4 , which facilitates the insertion of the strap.

D and E are sections of a tracing to which my invention is applied, the portion E being attached to the collar or hames of the harness and the portion D being attached to the singletree or other portion of the vehicle.

55 The tongue-plate B' and frame b' of the member B are of quadrant shape in side view, as clearly shown in Fig. 2. The portion b' is 60 to be attached to the trace, and when in its operative position the tongue on the trace has a tendency to normally press the pintle or tongue b upward or toward the strap, holding the same firmly in its place and locking 65 it in a firm and secure manner.

The trunnions or journals b^2 rest in the bearings a and oscillate within the same, so that the buckle may readily be thrown into or out of operative position with relation to the harness.

70 As will be readily seen, the two parts constituting my device may be manufactured separately and easily assembled, making a neat and efficient buckle which will possess 75 great strength and have the minimum number of parts.

The operation of the device is as follows: The portion b' being attached to the strap the member A is passed over the same, and the 80 pintles b^2 are placed in the bearings a , the tongue b normally resting on the outer portion of the bar a^2 of the frame A. The other end of the strap is passed through the opening between the bars a' and A' and between 85 the triangular tongue-plate B' and the bar a^3 , and the tongue B is passed through the perforations in the strap and through or into the keeper C. The greater the tension exerted on the strap the greater the binding 90 force of the buckle.

95 One of the great advantages of a buckle of this kind is its use with traces and heavy harness, where great difficulty is always found in manipulating the ordinary buckle. The stiffness of the leather, particularly when getting old, makes it difficult to insert the tongue in the perforations in the same. By my device, however, this objection is obviated, the construction of the same being such that the 100 tongue may be inserted with ease and dispatch. Furthermore, any catching of the reins or horse's tail in the same is prevented.

Having now fully described my invention,

what I claim as new, and desire to secure by Letters Patent, is—

1. In a buckle, the combination with the main rectangular member thereof, having upper and lower bars lying in different planes, the lower bars having a cross-piece connecting its side pieces, a second member adapted to be pivotally connected to the first, a triangular piece extending from the axis of the second member and carrying the tongue of the buckle, a frame also extending from the axis of said member for attachment to the harness, and a frame also extending from the axis of said member for attachment to the harness.
2. In a buckle, the combination with the main member thereof provided with bearings,

a second member having journals resting in said bearings, a triangular piece extending from the axis of the second member and carrying the tongue of the buckle, a frame also extending from the axis of said member for attachment to the harness, and a friction-roller journaled on the axis of the second member.

In testimony whereof I affix my signature in the presence of two witnesses.

L. D. RANK.
